UNITED STATES PATENT OFFICE.

ADOLF FREDRIK AHLBERG, OF STOCKHOLM, SWEDEN, ASSIGNOR TO AKTIEBOLAGET
SEPARATOR, OF STOCKHOLM, SWEDEN.

DEVICE FOR REMOVING AND REPLACING THE CONICAL DISKS IN A CENTRIFUGAL SEPARATOR-BOWL.

No. 905,826.

Specification of Letters Patent.

Patented Dec. 8, 1908.

Application filed October 11, 1906. Serial No. 338,443.

To all whom it may concern:

Be it known that I, ADOLF FREDRIK AHLBERG, a subject of the King of Sweden, and residing at Stockholm, Sweden, have invented certain new and useful Improvements in Devices for Removing and Replacing the Conical Disks in a Centrifugal Separator-Bowl; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My present invention relates to an improvement in such devices as are used for cleansing the conical plates in a centrifugal separator bowl. For this purpose a device has been used consisting of a number of parallel rods, which are secured to each other by means of rings or the like and which, when the device is put on the central feed pipe of the bowl, will form a continuation of the ribs on the central feed tube,

My present invention has for its object a simplified device which is not, however, adapted to form a continuation of the central feed tube. My improvement consists in a device formed from a single wire which is bent in such a manner that it forms a num-

ber of parallel rods, which are connected with each other by means of other parts of the wire.

The drawing shows a perspective view of a device according to my present invention, with one plate thereon. The wire begins at *a* and ends at *b*. It is bent in such a manner that three parallel rods *c* are formed, which at the top and bottom are connected with each other by other parts of the wire. In order to prevent the plate *d* from gliding away from the device, the rods *c* are formed into turns *e* at their bottom ends.

For the purpose of stiffening the rods *c* plates or the like *f* may be placed between them and secured to them.

What I claim is:

A device for cleansing conical plates of centrifugal separators, consisting of a wire bent so as to form a series of parallel rods connected to each other at the top and the bottom by other parts of the wire, adapted to receive the plates thereon, and allow them to be moved away from each other to be accessible on both sides.

In testimony, that I claim the foregoing as my invention, I have signed my name in presence of two subscribing witnesses.

ADOLF FREDRIK AHLBERG.
